UNITED STATES PATENT OFFICE.

CHARLES H. MELVIN, OF MOLINE, ILLINOIS, ASSIGNOR TO DEERE & COMPANY, OF MOLINE, ILLINOIS, A CORPORATION OF ILLINOIS.

PLOW.

1,306,705.

Specification of Letters Patent. Patented June 17, 1919.

Application filed February 28, 1914. Serial No. 821,792.

To all whom it may concern:

Be it known that I, CHARLES H. MELVIN, a citizen of the United States, residing at Moline, in the county of Rock Island and State of Illinois, have invented certain new and useful Improvements in Plows, of which the following is a specification, reference being had herein to the accompanying drawing.

10 This invention relates to plows, and more particularly to means for securing the share of the plow body in position.

A plow share, particularly in a traction plow, must be frequently removed for 15 pairs, sharpening, and the like; and the present improvement seeks to provide simple and effective means which will rigidly and securely hold the share in position, but which can be readily disengaged to permit 20 the removal of the share.

The invention consists in the features of improvement hereinafter set forth, illustrated in the preferred forms in the accompanying drawings and more particularly 25 pointed out in the appended claims.

In the drawings—

Figure 1 is a side view of a plow embodying my invention.

Fig. 2 is a bottom view showing the share 30 connecting means.

Fig. 3 is a perspective view of the share detached.

Fig. 4 is a fragmentary sectional view of the share securing bolt, taken along the line 35 4—4 of Fig. 2, and on a larger scale.

Fig. 5 is a fragmentary sectional view taken along the line 5—5 of Fig. 2, and on a larger scale.

Fig. 6 is a fragmentary sectional view 40 taken along the line 6—6 of Fig. 1.

Fig. 7 is a section through the abutment lug for the tightening bolt taken on a plane at right angles to that of the section in Fig. 4, and showing also the bolt.

Fig. 8 is a plan view of a plow body embodying the invention having some of the parts made in modified forms.

The main elements of the plow are, first, the body, which includes the moldboard, the 50 landside, the share (generally including the point), and the frog, and, second, the standard and beam.

In some body structures each of these main elements is made in two or more parts, 55 and in other cases all the parts of each ele-

ment are initially formed integrally, or with their detail parts rigidly fastened together.

In the present instance the main elements of the body, that is to say, the moldboard, the landside and the share, and the frog for 60 connecting these parts, are considered as entireties, approximately of the usual construction, being particularly designed, however, in such way that the share is not bolted in the old and ordinary fashion directly to 65 the share, but in such way that the share (the most rapidly wearing part) can be removed for sharpening or for the substitution of another.

In the present structure the moldboard is 70 indicated by *a*, the landside bar by *b*, the lower end of the plow beam or standard by *d*, and the share by *f*. The lower end of the plow beam is rigidly held in proper relation to the parts constituting the body by a pair 75 of bolts 1 which extend through the lower end of the beam, and through adjacent parts of the frog. The forward end of the landside bar is connected to the frog by bolt 2.

The share *f* lies upon the upper face of the frog *c* and is provided with a landside flange *f'* which engages the landside flange *c'* of the frog.

The rear end of flange *f'* abuts against the 85 forward end of the landside bar *b*. The flange is provided with a horizontal projecting stud or abutment 6 which extends inward and lies below an opposing surface as at 7 on the toe part of the frog. Preferably, in the forward portion of the landside *c'* of the frog there is formed a seat or aperture 6^a furnishing the inclined shoulder or surface 7 for engaging with the stud or abutment 6, as clearly shown in Figs. 1 90 and 6. The shoulders 7, 7^a are, in the specific form shown, provided by forming a slot in the landside flange *c'* of the frog; these shoulders being the upper and lower walls or edges of such slots. But I do not restrict 100 myself to this specific form of abutting device for the lug or lugs 6, 6^b.

The stud or abutment 6 assists in preventing the vertical movement of the forward part of the share relatively to the 105 frog. The toe portion of the frog fits snugly between the inner face of the flange *f'* of the share and an abutment 8 on the under face of the share. The frog is, at the landside of the structure, secured to the moldboard *a* by 110

the nuts and the bolts 4^a, and, at the other side, by bolt at 4. 9 is a fastening bolt connected to the share by a short bolt passing through the latter. The main bolt 9 extends 5 longitudinally and rearwardly from its point of connection with the share, and its rear threaded end extends through an opening 11 in an abutment part 11^a connected to the moldboard, and is provided with a 10 nut 12. By screwing up the nut 12, the share *f* is drawn rearwardly through the medium of the fastening bolt 9 to bring the parts thereof snugly into engagement with the frog, and the moldboard, and draw 15 the edge *f*² of the landside part of the share snugly against the front edge of the landside bar *b*.

The main body portion of the frog *c* on one side of its toe portion is cut away or 20 notched as at 13 to form a shoulder 14 which engages the abutment or head 8. This shoulder is preferably slightly inclined in rearward direction away from the landside flange *c*' of the frog, so that, as the share is 25 drawn rearwardly by the bolt 9, the shoulder 14 will have a wedging or camming action against the head or abutment 8. The flange *f*' of the share is thus drawn snugly against the landside *c*' of the frog and the stud 6 30 on the flange forced securely into engagement with the seat or shoulder 7.

The abutment 8 has a bolt 10 surrounded by a piece of metal 10^a which takes the wear from the bolt and is provided with a nut 10^b 35 which holds the piece of metal around the bolt in place when the latter is subjected to lateral pressure. The metal piece 10^a around the abutment bolt 10 is constructed to engage the under surface of the frog in 40 order that the bolt and nut shall have a broad bearing upon the lower face of the frog near its front edge, this part of the metal wearing piece being flared or flattened at its lower end, as shown; and the under 45 surface of the front edge of the frog is beveled or rounded where it engages with the part mentioned. With this arrangement there will be a wedging or camming action between the frog and the bolt 10 and nut as 50 the latter are drawn rearward by the nut 12; and the share is thus drawn snugly into engagement with the face of the frog and is securely held against springing away from the frog. A bolt 15 extends through the 55 outer portion of the share *f* and is provided on its lower end with a nut 17. This bolt is used to hold the forward end of the main draw bolt or fastening bolt 9. In order to have it far enough back from the bottom 60 of the furrow, and at the same time extend the frog metal forward, a recess 18 is provided for it in the outer part of the frog. When the share is in position, the nut 17 assists in holding it against vertical dis- 65 placement.

I shall herein refer to the forward portion of the frog as the "toe," to wit, the part that lies in front of the vertical plane passing through the abutment device 10 at right angles to the landside. This toe part 70 extends from the camming edge of the shoulder 14 to the outer surface of the flange *c*'. It is shown with a recess at *c*² for the preferable disposition of the bolt 9, there being on each side of this recess the 75 parts *c*³ and *c*⁴, respectively. It fits snugly between the head or abutment 8 and the landside flange *f* of the share and securely holds the share against lateral movement relatively to the frog. The engagement of the devices at 10^a and 10^c with the underside 80 of the frog, and the engagement of the stud or abutment 6 with the shoulder or edge at 7 on the frog, prevent the vertical movement of the share. 85

The share may be readily removed by loosening the nut 10^b on the bolt 10, and by removing the nut 12 on the fastening bolt 9. Then by tapping on the bolt 9, the share is forced longitudinally away from the other 90 parts of the plow body.

It should be noted that the abutments 6 and 8 which are secured to the share are engaged with the shoulders 7 and 14 on the frog and are disengaged therefrom first, by 95 a longitudinal movement of the share relatively to the frog and then by slight lateral movement to separate the abutment 8 from the walls of the recess around the shoulder 7. In replacing a share, the parts are assembled and the share snugly drawn into engagement with the other parts of the plow body by tightening the nut 12. When this is done, the shoulder 14, as stated, has a wedging or camming action against the 100 head or abutment 8 to draw the flange *f*' and stud 6 of the share snugly against the landside flange *c*' and the shoulder 7 while the front part of the frog has a wedging or camming action against the parts at 10^a, 10^b, and 10^c, and draws the main portion of 110 the share snugly into engagement with the face of the frog. After the nut 12 is tightened, the nut 10^b on the bolt 15 is tightened to hold the heel or outer part of the share 115 securely in place. The improved construction serves to rigidly hold the share in position while permitting the ready removal of the share for repairs, sharpening, or the like. 120

The metal piece at the abutment 8 which receives the direct contact with adjacent parts is shown as a short tube 10^a which surrounds the bolt 10. Its lower end is expanded or flattened, as shown at 10^c. 125

The metallic piece 10^a is of such axial length as to permit the head part 10^c to be forced down by the nut 10^b so as to get a clamping on the under side of the frog after the latter has been drawn to place by nut 9. 130

It will be seen that the parts constituting the frog are those which provide a common connecting abutting and holding device for the other main elements, the moldboard, the share, etc.

As above noted, the frog, as an entirety, has been designated by *c*. It can be regarded as composed of two sections *c*³, *c*⁴, the larger section *c*³ being formed as a curved plate integral with the landside flange *c*'. The section *c*⁴ of the frog is an extension thereof which projects in a direction away from the landside and from the main plate *c*³ well across toward the inner end of the share. This section can be regarded as made up of a part *c*⁵ arranged to extend forward across the transverse line between the share and the moldboard, and a part *c*⁶ arranged to be secured, if desired, to the moldboard.

The recess at 13 and the one at 18, above referred to, are preferably formed in or near this extended part *c*⁴ of the frog in order to advantageously apply the stresses which are intended to draw the share to its seats and hold it in place.

But in respect to these details, there can be modification, as, for example, in the location of the fastening bolt 9, nearer to or farther from the landside.

And, again, as above remarked, the invention is not dependent on the precise details of the main elements, respectively. In instances in the earlier art, the moldboard element has been formed of several pieces; the element herein referred to as the share has been made in separate details, (such as the point, the share proper, and the landside flange); and the frog element has also been made of several parts which were separable, to meet one or another purpose. Hence, the term "frog" is herein used to indicate that main element of the plow body (whether made in one part or in two or more) which, as an entirety, effects the binding together of the other main elements and holding them in their proper relative positions.

Thus, in Fig. 8, I have shown a modification of the plow body in which case the standard, the moldboard, the share and the fastening bolt, are in structure, conformation and relationship, identically the same as they are in the structure, shown in Figs. 1 to 7; and are, therefore, indicated by the same characters, *a*, *b*, *d*, and *f*; and the share, here, having the same landside flange *f*', the same stud or abutment 6, and the same abutment at 8.

The frog here meets the same ends, as does that in Figs. 1 to 7, but is also intended for a supplemental purpose. The two sections *c*³ and *c*⁴ (which are formed integral in the construction shown in Figs. 1 to 7 and are well adapted for use in large plows) are, in the form presented in Fig. 8, made sepa-

rately and then adjustably secured together so as to provide for flexibility between the two main parts of the frog, whereby delicacy of fit and tightness of union can be obtained when used with the several elements 70 of a smaller plow; and they are indicated in Fig. 8 by *c*⁸ and *c*⁹. The part *c*⁸ is provided with a fastening device at *c*¹⁰ for securing to it the other part *c*⁹, of the frog. It also has a forward extending section *c*⁵ on which is 75 formed the camming edge of the shoulder at 14 for drawing the share inward; and has also the rear part *c*⁶. The latter is preferably, but not necessarily, secured to the moldboard by the bolt 4. The end part of 80 this section *c*⁶ is slotted as at *c*¹¹, and through the slot passes the bolt *c*¹⁰.

The lug 11 through which the fastening bolt 9 passes, serves as an abutment for the drawing and binding bolt 12.

If there should be any slight misfitting of the parts (which is apt to be relatively magnified in the smaller plow bodies) the two sections of the frog, at *c*⁸ and *c*⁹, in this construction, will provide accommodation for 90 such irregularities. The two bolts at 4 and *c*¹⁰ are so aligned that they furnish a rigid line, in respect to the moldboard and the landside, in relation to which the abutment at 11 is held rigidly for imparting to the 95 share the stresses necessary for drawing it upward, inward, and backward. At the same time the part *c*⁹ of this frog can, without losing any of the effect of such alinement, adjust itself or be adjusted, as required, so that it will accommodate itself to very slight irregularities in the fitting or seating of the landside of the share to the frog and to the stationary part *b* of the landside.

The forward projecting toe part of the frog in this construction is similar to the corresponding part in Figs. 1 to 7, this toe part extending from the camming edge of the shoulder at 14 in Fig. 8 to the outer 110 surface of the landside flange *c*' of the frog, and fitting between the landside flange on the share and the abutment at 8.

The frog in this construction, as in the other, extends over the stud or abutment 6. 115 In both cases, the inclination of the shoulder at 7 in the frog insures that the landside flange of the share shall be held against rising too far, though drawn somewhat upward by the shoulder 7^a as it moves 120 backward. Consequently the rear end edge *f*² of the share flange (which is inclined somewhat downward and backward) is drawn under the front edge *b*' of the rigid landside bar *b*, and is also drawn somewhat upward to effect a tight junction at the line of contact of these edges. And, further, and at the same time, the rear end portion *f*³ is drawn up until it is brought snugly against the under surface of the 130

moldboard at its lower landside corner, the lower portion a' of the moldboard extending below the transverse planes of the contact line at f^2 . These matters insure not only a perfectly smooth continuous surface along the landside face of the share flange f' and of the landside bar b , but also a strong snug fit between the moldboard and the share, both along the transverse inclined line of their contact, and also immediately under the lower corner edge of the moldboard at the landside; both this part of the moldboard and the landside bar b serving as an abutment to lock the landside portion of the share in proper position, and allowing it to be drawn farther toward its seat after a preliminary contact.

The stud or projection 6 is inserted in an aperture in the flange f' of the share and is preferably strengthened and locked in position by forming it of round rod iron which is bent so as to be of U-shape or staple shape, the other stud-like leg 6^b also passing through the share flange, and both of the outer ends being upset and seated in countersinks as shown in Fig. 6. The connecting part 6^c , while not essential, gives an elongated bearing for the lug element on the opposing shoulder at 7 in the recess or aperture 6^a .

What I claim is:

1. The combination of the moldboard, the land side, the detachable share with a land side flange, the stud 6, and the abutment 8, the frog having the shoulder 7 engaging vertically with said stud the extension projecting away from the land side and the abutment 8 and formed with the shoulder 14 engaging with the said abutment on the share, and the drawing and locking bolt pivotally connected to the share and provided with a nut engaging with an abutment whereby the said bolt can, under the camming action of the stud 6 and abutment 8, be caused to draw the share longitudinally of the land side and transversely of the moldboard and lock the stud 6 and shoulder 7 in engagement and lock the shoulder 14 and abutment 8 in engagement.

2. In a plow body, the combination of the moldboard, the land side, the share having the land side flange f' , the stud 6 and the abutment 8, the frog bolted rigidly to the

moldboard and to the land side and having the section c^4 with a shoulder 14 engaging with the abutment 8 to draw the stud 6 into the vertical planes of the land side of the frog and a tightening bolt pivotally connected to the share and means carried by the frog co-operating with the bolt to cause the share to abut against the mold board, as set forth.

3. In a plow body, the combination of the land side, the moldboard having an extension a' projecting forward of the land side, the share having the land side flange f' with the rear end part f^2 fitted to the forward end of the land side and under the projecting part of the moldboard and having the stud 6, the frog having the shoulder 7, 7^a , and means interposed between the share and the moldboard for drawing the share backward to the moldboard and to the land side.

4. In a plow body, the combination of the moldboard, the land side having the upward and forward inclined front edge b' , the detachable share having the land side flange f' with the upward and forward inclined end edge f^2 , and the stud 6, a frog having a shoulder 7, and means for drawing the share backward toward the moldboard and the land side, substantially as set forth.

5. The combination of the moldboard, the land side, the share having the land side flange, the frog detachably locked vertically to the share at the land side and formed in two sections detachably connected together, one section being locked vertically to the share as aforesaid and the other section locked horizontally to the share, the bolt pivoted to the share and means carried by the frog and co-operating with the bolt to draw the share against the front edge of the moldboard and against the upper surface of the frog and bring the locking parts into operative positions, said two sections being movable relatively to each other when the share is detached but rigid in relation to the share when it is in working position.

In testimony whereof, I affix my signature, in presence of two witnesses.

CHARLES H. MELVIN.

Certificate of Correction.

It is hereby certified that in Letters Patent No. 1,306,705, granted June 17, 1919, upon the application of Charles H. Melvin, of Moline, Illinois, for an improvement in "Plows," errors appear in the printed specification requiring correction as follows: Page 1, line 66, for the word "share", first occurrence, read *frog*; same page, lines 75 and 76, strike out the words "by a pair of"; page 2, line 2, after the word "bolt", second occurrence, insert the word *privately*; same page, line 87, after the word "loosening" insert the words *if necessary*; same page, line 89, after the comma insert the words *or on the end of the share itself*; same page, line 114, after the comma insert the words *(if previously loosened)*; page 3, line 92, for the letter "c'" read *c¹⁰*; same page, line 97, beginning with the word "At" strike out all to and including the word "landslide.", line 105; and that the said Letters Patent should be read with these corrections therein that the same may conform to the record of the case in the Patent Office.

Signed and sealed this 29th day of May, A. D., 1923.

[SEAL.]

KARL FENNING,
Acting Commissioner of Patents.
